CLAIM

The ornamental design for an ear guard, as shown and described.

DESCRIPTION

FIG. 1 is a front perspective view of an ear guard, showing my new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

The drawings show the design of an ear guard suitable for being worn against a left ear.

The ornamental design also includes the mirror images of the drawings, i.e., the design of an ear guard suitable for being worn against a right ear.
